WASH BOX WATER CONTROL

Albert J. Sayers, Chicago, Ill., assignor to Link-Belt Company, Chicago, Ill., a corporation of Illinois

Application July 30, 1930. Serial No. 471,622

21 Claims. (Cl. 209—500)

This invention relates to a means and a method for controlling the water level in wash boxes.

It has for one object to provide a means and a method for use in an installation in which two or more wash boxes, positioned at different levels and maintaining different overflow levels, are operated in tandem and supplied from the same water range.

Another object is to provide in connection with such an installation means for preventing the undue draining of the upper box by the lower. Another object is to provide in such an installation means whereby the overflow level of the upper box is maintained at a pre-determined point independent of and unaffected by the overflow level of the lower box.

Other objects will appear from time to time in the specification and claims.

My invention is illustrated more or less diagrammatically in the accompanying drawings, wherein—

Figure 1 is a side elevation of a wash box installation to which my control has been applied, with parts broken away and parts in section;

Figure 2 is a plan view of the same;

Figure 3 is a transverse vertical cross section taken at line 3—3 of Figure 1 at a point between the two wash boxes;

Figure 4 is a transverse vertical section on an enlarged scale showing the adjustable weir;

Figure 5 is a vertical cross section showing the adjustable weir in a vertical plane which lies at an angle of 90° with relation to the plane of Figure 4.

Like parts are designated by like characters throughout the specification and drawings.

One form of wash box to which the structure of my present invention may be applied, is illustrated in my application Ser. No. 411,646, filed December 4, 1929. While my invention is not limited to associate with the particular wash box shown in that application and while it is not in fact limited to use in a wash box of any type, it has particular importance when associated with a plurality of wash boxes of the type shown in that application. I have shown a pair of wash boxes arranged in tandem with my control applied to them. More than two wash boxes might be arranged to operate together, using the same water range and using or not using the same air range, as the case may be.

For purposes of simplicity, I have shown only two wash boxes connected in tandem. They are substantially identical in construction with each other. Each is formed generally of a container A, having a rounded bottom A¹ and carried by suitable supports A². On the bottom of each is a trough A³ into which some refuse falls and which has within it a screw conveyor A⁴ which

moves the material to an elevator A⁵ within a housing A⁶ from which material is discharged into a hopper A⁷ communicating with a chute A⁸. The material is thereafter conveyed to any suitable point. A⁹ is a partition situated in the upper part of the chamber formed within the member A and extending end to end but stopping short of the bottom of the chamber. Thus in effect the partition A⁹ divides the upper part of the container A into two longitudinally disposed chambers. A¹⁰, A¹⁰ are transverse vertical partitions which further divide the space within the member A into smaller compartments. Situated in the top of each of these compartments and to the right of the partition A⁹, as shown in Figure 3, is a valve assembly A¹¹, to which air under pressure is furnished by means of a pipe A¹² from a header A¹³. A¹⁴ is a valve operating assembly by means of which the valves are opened and closed so as to discharge air through the valve A¹¹. By means of this air, water within the housing is forced from the right beneath the partition A⁹ and upward through the sieve A¹⁵. One such sieve is positioned in each of the wash boxes and is preferably inclined from the receiving end of the box to the discharge end of the box so that material which is fed upon the sieve will tend to move from one end of it to the other, that is to say, from left to right, as indicated in Figure 1, and water is constantly being forced through the sieve by means of the air pressure which is applied to it through the opening and closing of the valves A¹¹. A¹⁷ is a valve.

B is an inlet chute by means of which coal, for example, is conveyed to the left hand wash box as shown in Figure 1. This box is provided with an outlet connection B¹ which is generally on a level with the discharge right hand end of the sieve A¹⁵. Communicating with the upper part of the left hand wash box is a chute B². This chute is at a level above the outlet B¹ and coal being lighter than the refuse, will, of course, work to the top and pass out through the chute B², while the heavier refuse will work down and pass out through the refuse outlet B¹, and from there is goes to one of the refuse conveyors A⁵. The chute B² discharges into the right hand wash box and thus onto the sieve A¹⁵ of that wash box which is provided with a refuse outlet B³ and an outlet B⁴ for washed coal. The chute B² may have in it a perforated plate B⁵ which is positioned above a water discharge compartment B⁶ from which a pipe B⁷ leads. The discharge through the pipe B⁷ is controlled by a valve B⁸. Thus as coal flows from the wash box unit on the left hand to the wash box unit on the right hand, as indicated in Figures 1 and 2, some of the water will discharge through the perforated plate and to some extent the coal will thus be dewatered.

C is a water header positioned to supply water

to the left hand wash box as indicated in Figure 1. C¹, C¹ are pipes, one of which runs from the header to each compartment. They may be controlled by valves C². C³ is a water header positioned to supply water to the right hand wash box as shown in Figure 1. Communicating with it are pipes C⁴, C⁴ which are positioned to supply water to each of the compartments of the right hand wash box and they are provided with valves C⁵. C⁶ is a member to which the headers C and C³ are connected. A fixed portion C⁷ is positioned in the member C⁶ and a movable partition C⁸ is positioned to form an adjustable continuation of the partition C⁷. The partition C⁸ may be raised and lowered by a control member C⁹. C¹⁰ is an opening. It may be closed by a plate or other means. The partition C⁷ and the movable partition C⁸ furnish a weir, adjustable in height and positioned in the path of the water as it flows through the headers C and C³. By means of the weir, the level of the water in the left hand wash box may be held at any suitable point, irrespective of the level of water in the other wash box. C¹¹ is a valve controlling the flow of water to the header C and consequently controlling the entire supply of water to both wash boxes.

It will be realized that whereas I have herewith shown and described a practical operative device, nevertheless many changes might be made in the size, shape, number and disposition of parts without departing materially from the spirit of my invention and I wish, therefore, that my showing be taken as in a sense diagrammatic. In particular, while I have shown an adjustable weir for controlling the level of coal in wash boxes, my invention is not limited to this apparatus. The level of the water might be controlled by many other means, and any apparatus which would control the level of water in one wash box substantially independent of the level in another wash box joined to it, is within the contemplation of my invention.

The use and operation of my invention are as follows:

45 With two or more wash boxes arranged in tandem, to be supplied by water from the same water range, as indicated in the drawings, if nothing were provided to control the level of the upper or left hand wash box, as shown in Figures 1 and 2, the water would naturally flow from the upper box and approximate the level of the water in the lower or right hand box. The water, if free to do so, will also by-pass through the supply pipe or header C into the second or lower box and thus the lower box will control the level of the water in the upper box and will act to drain that box and reduce its level to the level of the lower box. Since the level at which the water should stand in the upper box is higher than the level at which it should stand in the lower box, the upper box cannot operate satisfactorily unless some control of its water level is provided. It is to accomplish this purpose that the upwardly extending member C⁶ is provided as a connection between the headers C and C³. The upper level of this member C⁶ is above the overflow point or the level at which water should stand in the higher box.

Water will flow from the header C into the member C⁶ and out of that member into the header C³ from which it moves into the lower box to supply it with water. However, before water flowing from the header C into the member C⁶ can escape from it, it must flow over the partition or weir formed of the members C⁷ and C⁸.

The member C⁸ which is adjustable, controls the level of the water in the upper chamber because water leaving that chamber must flow over the member C⁸. This member will be adjusted to a height suitable to maintain a proper level of water in the upper chamber, and the adjustable weir is thus effective to control the level of water in the upper chamber no matter what the level of the water in the lower chamber may be. The member C⁶ is provided with an opening C¹² which is in effect a vent to prevent siphoning of water from the higher to the lower box. As I have stated above, the adjustable weir is not the only means which might be used to accomplish this result. This construction, however, is preferred to one employing individual pipes leading from the water supply to each wash box as this would require an additional number of valves and would make an installation which would be more expensive and more difficult to operate. By arranging the water range as shown in the drawings, that is to say, by arranging the headers C and C³ and the member C⁶, one control valve may be used for handling the water and for shooting it down the plant.

In the normal operation of the machine, the individual valves C² and C⁵, leading to the several compartments in the first and second or upper and lower boxes, will be adjusted for the particular gravity of the coal or other material which is being washed. After these valves are once set for the proper gravity, they will normally require no change. The control thereafter is effected by opening or closing the main valve which controls the entire water supply. This may be done to meet varying tonnages of material as delivered to the box over a day's run.

While I have shown two wash boxes mounted in tandem and provided with my water level control, more than two might be so associated and the same arrangements for controlling the level between each two boxes would be used. The water control of this application is not necessarily limited to association with the particular means of supplying air shown. The air which is admitted from the header A¹³ through the pipe A¹² controlled by the valve A¹⁷ and the valve A¹¹ might be otherwise supplied.

In the usual operation only a very small part of the refuse normally passes through the perforated plate or sieve due to the building up and maintaining of a refuse bed upon the sieve. Most of even the smallest refuse is held within the bed and carried with it and is therefore not passed through the sieve and does not settle into either of the troughs A³.

Where I have used the expression sieve I mean a screen, a sieve, a perforated plate or sieve plate or any similar device or equipment which may provide a support to hold the mass of coal and its impurities in a bed above the wash box chamber. The perforations in this element provide apertures for the movement of the water upward through the mass. The term sieve where it occurs is therefore to be understood in this sense and not as comprising a means for sizing the material.

The operation of the air valve A¹¹ does not form the particular part of the present invention. It is sufficient to say, however, that the valve when in one position permits a given flow of air to pass into the air section of the wash box, thus displacing an equal volume of water and forcing it through the perforated plate and material in the wash box, thus causing the material to stratify

according to specific gravity. The valve when in another position cuts off the flow of air to the air section of the wash box and permits the air under pressure to discharge into the atmosphere. The intensity of movement caused by the application of pressure in the air section and its release is controlled by the movement of valve which in opening and closing sets up movement of the entire mass of water associated with its particular

section of the wash box. In other words one function of these valves is to create an upward current through the mass of material being treated and to permit the material to return by gravity to rest without the creation of a downward suction. An important feature in the operation of the wash box is the fact that the supply of air and water to each cell or division of the wash box is controlled. Valve A¹⁷ in a pipe A¹² permits an adjustment to provide a varied pressure flow and quantity to each cell from the main air headers A¹³. The position of this valve controls the pressure in each cell. Similar control of the water from the headers C and C³ is accomplished by adjustments on valves C² and C⁵.

Under certain conditions after the coal passes from one wash box to the next it is necessary to prevent the accumulation of too much water in the second box. This may not always be necessary as this second box is usually provided with a larger wash box than the first and this arrangement of second box will therefore provide for excess water. Where, however, the second box is not sufficiently large or where for any other reason de-watering is desirable, the perforated plate E⁵ is effective for that purpose.

I claim:

1. In combination, an upper and a lower water container, a single water supply member, conduits connected between said supply member and said containers whereby water from said member is discharged into each of said containers, and an obstruction other than said containers in the path of said water, adapted to control the level in the upper container irrespective of the level in the lower container, said obstruction comprising an adjustable weir and means, independent of the water supply, for causing pulsations of the water in the said containers.

2. In combination, an upper and a lower water container, a single water supply member, communicating first with one and then the other, whereby water flows through said member and is discharged into each of said containers, and an obstruction apart from said containers in the path of said water, adapted to control the level in the upper container irrespective of the level in the lower container, said obstruction comprising an adjustable weir and means, independent of the water supply, for causing pulsations of the water in the said containers.

3. In combination with two water containers, each having an overflow, that of one being higher than that of the other, a single means for supplying water concurrently to said containers and means other than the containers and positioned within the water supply means for controlling the level of water in one container independent of that in the other while maintaining the flow of water to both of said containers and means, independent of the water supply, for causing pulsations of the water in the said containers.

4. In combination with two water containers, each having an overflow, that of one being higher than that of the other, a single means for supplying water to both containers concurrently, and

means in addition to the containers and positioned within the water supply means for controlling the level of water in one container independent of that in the other while maintaining the flow of water to both of said containers, said means including a water passage between the two, and means, independent of the water supply, for causing pulsations of the water in the said containers. 80

5. In combination with two water containers, each having an overflow, that of one being higher than that of the other, a single means for supplying water to each container, and means for controlling the level of water in one container independent of that in the other, said water supply means including a water passage between the two in addition to the overflow and an obstruction in the water passage, said obstruction controlling the water level in the container next above it while concurrently maintaining the supply of water to the container next below it and means, independent of the water supply, for causing pulsations of the water in the said containers. 85

6. In combination with two water containers, each having an overflow, that of one being higher than that of the other, a single means for supplying water to each container, and means for controlling the level of water in one container independent of that in the other, said water supply means including a water passage between the two in addition to the overflow and a movable obstruction in the water passage, said obstruction controlling the water level in the container next above it while concurrently maintaining the supply of water to the container next below it and means, independent of the water supply, for causing pulsations of the water in the said containers. 90

7. In combination in a coal washing assembly, a plurality of wash boxes, each box including a screen, means for pulsatingly forcing water upward through each screen, a single means independent of said pulsating means for supplying water to all of the boxes concurrently and means in the water supply means for controlling the level of water in each washer independently while maintaining the supply of water to all of the boxes. 115

8. In combination in a coal washing assembly, a plurality of wash boxes, each box including a screen, means for pulsatingly forcing water upward through each screen, a single means independent of said pulsating means for supplying water to all of the boxes and means in the water supply means for controlling the level of water in each washer independently, including an obstruction in the path of the water. 120

9. In combination in a coal washing assembly, a plurality of wash boxes, each box including a screen, means for pulsatingly forcing water upward through each screen, a single means independent of said pulsating means for supplying water to all of the boxes and means in the water supply means for controlling the level of water in each washer independently, including an obstruction in the path of the water, said obstruction movable and adapted to be positioned to control the level of the water in the washer next above it. 135

10. In combination in a coal washing assembly, a plurality of wash boxes situated at different levels, each box including a screen, means for forcing water pulsatingly upward through each screen, a single means independent of said 150

pulsating means for supplying water to all of the boxes and means in the water supply means for controlling the level of water in each washer independently.

5 11. In combination in a coal washing assembly, a plurality of wash boxes situated at different levels, each box including a screen positioned at an angle to the horizontal and being subdivided into a plurality of compartments, means 10 for forcing water pulsatingly upward through each screen, a single means independent of said pulsating means for supplying water to all of the boxes and means in the water supply means for controlling automatically the level of water 15 in each washer independently.

12. In combination in a coal washing assembly, a plurality of wash boxes situated at different levels, each box including a screen positioned at an angle to the horizontal and being subdivided into a plurality of compartments, means 20 for forcing water pulsatingly upward through each screen, a single means independent of said pulsating means for supplying water to all of the boxes and means for controlling the level 25 of water in each washer independently, including an obstruction in the path of the water outside of said boxes, said obstruction movable and adapted to be positioned to control the level of the water in the washer next above it.

20 13. In combination, a plurality of water containers provided with overflows and in addition, each provided with an outlet, no two outlets being at the same level, a single means for supplying water to said containers, said means being in communication with each of said containers, and including a weir-like part over which water must flow in passing to one of the containers having a low level outlet and means, 25 independent of the water supply, for causing pulsations of the water in the said containers.

45 14. In combination, a plurality of water containers provided with overflows and in addition, each provided with an outlet, no two outlets being at the same level, a single means for supplying water to said containers, said means being in communication with each of said containers, and formed to provide a part over which water must flow in passing from one container to the other, said part approximately on a level with the discharge point of the container next above it and means, independent of the water supply, for causing pulsations of the water in the said containers.

55 15. In combination, two water containers, a single water supply member, through which water flows and is discharged into each of said containers, and an obstruction in the path of said water within said supply member, adapted to control automatically the level in the first container, means for delivering the water passing over said obstruction to the second container whereby the level in the first container is maintained irrespective of the level in the second container and means, independent of the water supply, for causing pulsations of the water in the said containers.

65 16. In combination, two water containers, a single water supply member, through which water flows and is discharged into each of said containers, and an obstruction in the path of said water within said supply member, adapted to control automatically the level in the first con-

tainer irrespective of the level in the second container, said obstruction comprising an adjustable weir and means, independent of the water supply, for causing pulsations of the water in the said containers.

80 17. In combination, two water containers, a single water supply member, communicating first with one and then the other, through which water flows and is discharged into each of said containers, and an obstruction in the path of said water within said supply member, adapted to control the level in the first container, means for delivering the water passing over said obstruction to the second container whereby the level in the first container is maintained irrespective of the level 90 in the second container and means, independent of the water supply, for causing pulsations of the water in the said containers.

85 18. In combination, two water containers, a single water supply member, communicating first with one and then the other, through which water flows and is discharged into each of said containers, and an obstruction in the path of said water within said supply member, adapted to control the level in the first container irrespective of the level in the second container, said obstruction comprising an adjustable weir and means, independent of the water supply, for causing pulsations of the water in the said containers.

95 19. In combination, two water containers, a single water supply member, whereby water flows through said member and is discharged into each of said containers, and an obstruction in said water supply member, adapted to control the level in the upper container irrespective of the level in the lower container, and means for moving material from one water container to the other and for dewatering it as it passes from one container to the other and means, independent of the water supply, for causing pulsations of the water in the said containers.

105 20. In combination an upper and a lower water container, a single water supply member, conduits connected between said supply member and said containers whereby water from said member is discharged into each of said containers, and an obstruction other than said containers in the supply member to control the level in the upper container irrespective of the level in the lower container, while maintaining the delivery of water to said lower container from the supply member, and means independent of the water supply for causing pulsations of the water in said containers.

110 21. In combination, an upper and a lower water container, a single supply member, conduits connected between said supply member and said containers whereby water flowing through said member is discharged into each of said containers and an obstruction apart from said containers positioned in the supply member between the points of connection of the respective conduits with the supply member, whereby to control the level in the upper container irrespective of the level in the lower container, while maintaining delivery of water to said lower container from the supply member, and means independent of the water supply for causing pulsations of water in said containers.

115 ALBERT J. SAYERS.
